The Gates Rubber Company, Denver, Colo., a corporation of Colorado

Application August 19, 1953, Serial No. 26,509

Term of patent 14 years

(Cl. D9—6)

To all whom it may concern:

Be it known that I, Charles C. Gates, Jr., a citizen of the United States, residing at Denver, county of Denver, State of Colorado, have invented a new, original, and ornamental Design for a Floor Mat, of which the following is a specification, reference being had to the accompanying drawing, forming part thereof and in which:

Fig. 1 is a top plan view of a floor mat, embodying the design of this invention;

Fig. 2 is a fragmentary, oblique side elevation of a portion of the floor mat, taken from the position of line 2—2 of Fig. 1;

Fig. 3 is a fragmentary front elevation of a portion of the floor mat, taken from the position of line 3—3 of Fig. 1; and

Fig. 4 is a fragmentary perspective view of one corner of the mat.

The bottom of the mat, not shown because it does not form a dominant part of the present invention, is the reverse of the upper side, having elongated triangular recesses disposed in the same pattern as the projections shown in Fig. 1.

I claim:

The ornamental design for a floor mat, as shown and described.
